UNITED STATES PATENT OFFICE

ALBERT HERMAN KERSTING, OF GLENDALE, CALIFORNIA

SPRING SASH BALANCE

Application filed September 30, 1926. Serial No. 138,605.

My invention relates to a sash balance of the type wherein a coiled spring is arranged within and connected to a drum for imparting rotary movement thereto in one direction and there being a band or metal tape arranged to wind upon said drum with one end of said tape secured to the window sash.

The principal objects of my invention are to generally improve upon and simplify the construction of the existing forms of spring sash balances, to combine with the sash balance suitable means, preferably adjustable, for producing a certain degree of friction upon the window sash with which the spring balance is associated, which friction producing means acts as a brake or retarding element to prevent a too free movement of the sash as it is raised or lowered, and further, to provide a device of the character referred to that is relatively simple in construction, inexpensive of manufacture, and capable of being readily installed.

With the foregoing and other objects in view, my invention consists in certain novel features of construction and arrangement of parts that will hereinafter be more fully described and claimed and illustrated in the accompanying drawing, in which—

Fig. 1 is a vertical section taken through the center of a spring sash balance of my improved construction and showing the same associated with a window frame and sash.

Fig. 2 is an elevational view of a portion of a window frame and showing my improved sash balance positioned therein.

Fig. 3 is a detail elevational view, partly in section, of the lower corner of a window sash and showing a modified form of the friction producing means that is associated with the spring sash balance.

Referring by numerals to the accompanying drawing which illustrates a practical embodiment of my invention, 10 designates a face plate, preferably of metal, that is secured in any suitable manner, preferably by means of screws 11, to the face of the jamb 12 of a window frame, and formed in said jamb to the rear of the face plate is an opening or mortice 13 that is occupied by a housing 14. This housing is preferably stamped

or pressed from sheet metal and one side thereof is suitably secured to the face plate 10.

Secured to the side walls of housing 14 are the ends of a centrally arranged pin 16 and mounted for rotation thereon and positioned within the housing 14 is a hollow drum 17. The inner end of a coiled spring 18 similar to a clock spring is secured to pin 16 and the outer end of said spring is secured to the circumferential wall of drum 17.

Secured to the outer face of the peripheral wall of drum 17 is the inner end of a coil of metal tape 19 and the outer end of this tape passes through a slot or opening 20 that is formed in face plate 10 and the end of said steel tape is secured in any suitable manner to the lower portion of the stile 21 of the window sash.

In order that the window sash may have smooth, even movement when raised or lowered, it is desirable that there be associated with the spring balance some form of yielding pressure means that acts directly on the sash for producing a certain degree of frictional resistance and to accomplish this result, I propose to arrange between the stile of the sash and the jamb of the frame a resilient member, preferably a flat spring 22 that is secured in any suitable manner to the face plate 10 and the intermediate portion 75 of which spring is bowed outwardly so as to frictionally engage the corresponding face of the stile.

This flat spring extends downward directly in front of the face plate and the lower portion of said spring is preferably bifurcated for the accommodation of that portion of the tape 19 that passes downwardly from the opening 20. The lower portion of the friction producing member 22 may bear on the lower portion of the face plate 10 as illustrated in Fig. 1, or said lower portion may bear on the adjacent face of the stile 21 (see dotted lines Fig. 1).

Under normal conditions, or before the window sash is placed in the frame, friction producing member 22 projects outwardly from the jamb at a decided angle relative to a vertical plane and when the sash is placed in the frame with the stile adjacent to the 100

jamb, the friction producing member will be forced inwardly toward the jamb so that the central portion of the member 22 bears with a considerable degree of friction on the face 5 of the stile, and as a result said member 22 functions as a frictional brake to restrain the window against moving too freely while being raised or lowered.

It will be understood that when the lower 10 sash is closed, the tape 19 is practically all unwound from the drum 17 and the coil spring 18 within said drum is wound upon a pin 16 and that these conditions are reversed when the sash is moved to full open 15 position.

In order to vary the degree of frictional engagement between the spring 22 and the sash, an adjustable fulcrum or bearing may be provided for said spring and in Fig. 1, I 20 have shown a simple arrangement for accomplishing this result and which arrangement comprises a screw 23 that is seated in the face plate 10 beneath the spring, which screw bears against the inner face of spring 22. 25 Obviously by adjusting screw 23 in the face plate, the degree of friction produced by the spring may be varied. Screw 23 is adjusted by the insertion of the point of a screwdriver through an aperture in the spring and which 30 aperture is smaller than the head of the screw.

It will be noted that the resilient member 22 is directly connected to and positioned immediately in front of the face plate 10 of the spring balance housing and thus said 35 resilient member performs the functions of a combined face plate and frictional contact member. An especially desirable feature of this particular construction is that the work incident to the installation of the fixture in 40 the window frame is facilitated and, further, the face plate 10 of the spring balance provides a firm and substantial support or bearing for the resilient friction producing member, as well as for the screw 23 that is utilized 45 for controlling or regulating the tension or degree of friction produced by said resilient member.

In Fig. 3 I have illustrated a modified form of the friction producing means between the sash and window frame and which means includes a flat spring 24 having a bowed intermediate portion 25 and a horizontally disposed lower end portion 26. The upper end of this spring is secured in any 50 suitable manner to the lower end of the steel band or tape 19 and the horizontally disposed lower portion of said spring is secured to the underside of the stile of the window frame. When thus arranged, the bowed intermediate 55 portion 25 of the spring bears with yielding resistance against the face of the jamb, thereby producing the desired frictional braking action.

Thus it will be seen that I have provided a 60 relatively simple, convenient and inexpensive

arrangement whereby a variable friction braking element is combined with a sash balance and which combination enables the equipped sash to be freely raised and lowered with a relatively smooth movement and said sash will be firmly held at any adjusted position. 70

It will be understood that minor changes in the size, form and construction of the various parts of my improved spring sash may be 75 made and substituted for those herein shown and described without departing from the spirit of the invention, the scope of which is set forth in the appended claims.

I claim as my invention:

1. In a spring sash balance, a flat spring, means for securing one end of said spring to a window frame above the spring balance therein, the intermediate portion of which flat spring is bowed outwardly for contact with the sash operating in the frame, the lower end of said flat spring being bifurcated for the reception of the flexible member that connects the sash to the spring balance and there being a tool-receiving aperture formed in said spring intermediate its ends. 85

2. In a spring sash balance, a flat spring, means for securing one end of said spring to a window frame above the spring balance therein, the intermediate portion of which flat spring is bowed outwardly for contact with the sash operating in the frame, the lower end of said flat spring being bifurcated for the reception of the flexible member that connects the sash to the spring balance said 90 spring being provided intermediate its ends with a tool-receiving opening and the lower portion of said flat spring being bent inwardly for engagement with the window frame below the spring balance therein. 95

3. In a spring sash balance, a flat spring, means for securing one end of said spring to a window frame above the spring balance therein, the intermediate portion of which flat spring is bowed outwardly for contact with the sash operating in the frame, the lower end of said flat spring being bifurcated for the reception of the flexible member that connects the sash to the spring balance, and means adjustably arranged beneath the upper portion of the spring for regulating the degree of frictional engagement between said 100 spring and sash. 110

4. In a spring sash balance, a flat spring, means for securing one end of said spring to a window frame above the spring balance therein, the intermediate portion of which flat spring is bowed outwardly for contact with the sash operating in the frame, the lower end of said flat spring being bifurcated for the reception of the flexible member that connects the sash to the spring balance, means 115 adjustably arranged beneath the upper portion of the spring for regulating the degree of frictional engagement between said spring 120 and sash. 125

and sash, and said flat spring being provided with an aperture for the accommodation of a tool used in the manipulation of said adjustable means.

5 5. A device of the class described comprising a flat bow spring, one end of which is adapted to be secured to a window frame, the other end being bifurcated for the reception of a flexible sash supporting member, 10 and said spring being provided with an aperture for the reception of a tool utilized for adjusting tension regulating means located on the window frame to which the spring is applied.

15 In testimony whereof I affix my signature.
ALBERT HERMAN KERSTING.
